ADJUSTABLE EYE SHIELD

Raymond G. Woodard, East Orange, N. J., assignor
to Standard Safety Equipment Co., a corpora-
tion of Illinois

Application April 17, 1939, Serial No. 268,358

1 Claim. (Cl. 2-12)

This invention relates to a protective device for human eyes and more particularly to an improved means for supporting a transparent eye-shield on the head of a wearer.

5 The primary object of the invention is to provide a simple, reliable, and inexpensive protective device that will be comfortable and can be worn over eye-glasses without interference.

10 A further object of the invention is to provide a simple eye-shield which can easily be adjusted to any person's head and may be readily tilted to any angle to provide the desired eye protection. The device is adapted to protect the eyes of the wearer from the glare of artificial light, may 15 serve as a protection for flying particles of matter, such as are encountered when working on a grinding wheel, and the device is equally suitable for out-of-door use to protect the wearer from wind or sun glare. The device is designed so that 20 the shield itself is supported at but two points and preferably is adjusted so that an open air space is provided between the upper edge of the shield and the forehead of the wearer.

25 A further object of the invention is to provide an eye-shield of resilient, durable, transparent material, such as of cellulose acetate and to provide it with adjustable straps so that it may be laid flat for insertion in an envelope or the like and enable a number of the devices to be packed 30 compactly.

35 The invention is illustrated in a preferred embodiment in the accompanying drawing, in which: Figure 1 is a front elevational view of the device; and Figure 2 is a side elevational view showing the device fitted on the human head, one of the optional positions being indicated by dotted lines.

40 In the embodiment illustrated, A designates a flexible band adapted to snugly embrace the head 45 of a wearer, and is shown provided with an adjusting fastener A'; B, clips through which the band A is threaded and upon which the clips may be adjustably positioned; C, swivel-members which are hinged on the clips B; and D, a transparent resilient panel which is carried by the swivel-members C.

45 The head-band A may be of any suitable material such as an elastic or non-elastic tape, of the type used in garters and the like, and is of 50 sufficient length to fit around a human head. The fastener A' connects the end portions of the band adjustably and may be of any suitable construction.

55 The clips B are of known construction and comprise a loop shaped member 3 provided with

a loose cross-bar 4. The head-band is threaded through the clips so that the clips may be readily adjusted thereon when there is slack in the head-band.

5 The swivel-members C preferably are U-shaped members whose loop portions 5 fit around one of the bars on the clips B and have rounded leg portions 6 which embrace the upper corner portions of the eye-shield. The legs are perforated to receive a headed rivet or fastener 7 which 10 passes through the legs and perforations provided in the corners of the panel.

15 The window portion of the device D has a panel of substantially rectangular construction having rounded corners. The panel should be 15 made of fairly heavy, resilient, transparent, and wear-proof material which will provide clear visibility. If desired, the material may be tinted to eliminate light glare. Celluloid can be used, but it is preferred to use materials which are not so 20 inflammable. Cellulose acetate makes an excellent material as it has the desired characteristics and is not so brittle that it will not withstand rough usage. The upper corner portions of 25 the panel are perforated to receive the rivets or fasteners 7 and those corners are sufficiently rounded to permit the swivel-members C to turn with respect to the shield when the device is turned up, as indicated in Figure 2.

30 In adjusting the device the wearer first adjusts the fastener A' so that the head-band will snugly embrace the head as shown in Figure 2. The fasteners 3 are then adjusted on the head-band A so that the shield will be bowed outwardly. The amount of clearance between the shield 35 and the head of the wearer can be regulated in this manner so that air may circulate between the shield and the forehead of the user. If the device is to be used as an eye protection against flying fragments of material, it may be turned 40 down in the position indicated by the dotted lines in Figure 2. If it is used to prevent light glare, it may be turned up to the position illustrated by the full lines in Figure 2. The clearance between the shield and the head-band will permit such 45 movement.

45 There is a slight friction exerted by the swivel-members against the shield at all times, but this friction is considerably increased when the device is placed on one's head due to the resilience 50 of the shield and this friction is sufficient to hold the shield in any desired angular position. As will be readily seen, the clearance, which may be afforded by proper adjustment of the clips B, will enable the device to be used without interference 55

with spectacles or glasses on the head of the wearer.

The foregoing detailed description has been given for clearness of understanding only, and no unnecessary limitations should be understood therefrom, for some modifications will be obvious to those skilled in the art.

I claim:

An adjustable eye-shield comprising: a transparent, resilient eye-shield panel of substantially rectangular shape; a pair of U-shaped swivel-members pivotally secured to the upper corner

portions of said panel; an adjustable clasp pivotally secured to each of said swivel members; and a flexible head-band loop threaded through said clasps and adjustable lengthwise to fit a human head snugly, at least one of said clasps being adjustable longitudinally of the head-band whereby the air space between the head-band and panel may be regulated to accommodate eyeglasses of the wearer, if desired, and the panel may be tilted adjustably to a desired angular position.

RAYMOND G. WOODARD.
